UNITED STATES PATENT OFFICE.

ERNST SCHMITZ, OF CHICAGO, ILLINOIS.

MIXER FOR CULINARY USE.

No. 925,038.

Specification of Letters Patent. Patented June 15, 1909.

Application filed March 14, 1908. Serial No. 421,089.

To all whom it may concern:

Be it known that I, ERNST SCHMITZ, a citizen of the United States, residing at Chicago, county of Cook, and State of Illinois, have 5 invented certain new and useful Improvements in Mixers for Culinary Use, of which the following is a specification.

My invention relates to mixers for culinary use and particularly to mixers characterized 10 by a receptacle and a rotary dasher suspended therein.

The object of my invention is to provide a mixer of the class mentioned having a suitable frame, a receptacle removably mounted 15 therein, a rotary dasher detachably mounted in said frame and suspended within the receptacle and suitable drive mechanism fixed to said frame, and equipped with means for locking the receptacle and dasher in the 20 frame and means to prevent operation of the device except when in locked position.

A further object of my invention is to provide a device as mentioned, which shall be of simple construction, easy to operate, of low 25 cost to manufacture and one which shall not readily get out of order.

Other objects will appear hereinafter.

My invention will be more readily understood by reference to the accompanying 30 drawings forming a part of this specification, and in which,

Figure 1 is a front elevation of a mixer embodying my invention in its preferred form, Fig. 2 is a top plan view thereof, Fig. 3 is a 35 side elevation with a portion of the side of the receptacle broken away to show the dasher, Fig. 4 is a perspective view of the dasher, the parts being segregated and Fig. 5 is a horizontal section of the dasher near its upper 40 end.

The frame of the device comprises a base 1, a pair of uprights 2, a yoke 3 and an upper frame portion 4, from which a dasher is suspended and within which the driving mechanism is arranged. The base 1 is preferably 45 of wood but may be formed of metal if desired. The uprights 2 of the frame are formed of flat bars of metal having their lower ends bent in forming feet 5 by which 50 they are bolted or otherwise secured to the base. The members 2 extend vertically upward for a considerable distance and are then inclined inwardly as at 6, and their upper ends are bent in a horizontal position forming flanges 7 by which they are secured to a

horizontally disposed plate 8. The yoke 3 is riveted or otherwise secured to the vertical portions 2 at about midway of their height, and is arranged or provided with the parallel and horizontal arms or extensions 3'. The 60 upper frame 4 is formed of a single bar of metal bent to form the horizontal portion 9 which is secured to the plate 8, the vertical portion 10 and the horizontal upper arm 11 arranged above and parallel with the arm or 65 portion 9.

12 indicates the receptacle which is preferably a cylindrical member of thin sheet metal open at the top and having a rounded or hemispherical bottom 13. The receptacle is 70 provided with the trunnions 14 by which it is mounted upon the ends of the arms 3' of the yoke, the upper edges of the arms being provided with notches 15 to receive them. The trunnions are arranged above the center 75 of the receptacle hence the latter assumes an upright position when mounted in the frame. The receptacle is provided with a closure which comprises a disk 16 having a depending flange 17 which fits snugly about the upper edge of the receptacle. 80

The dasher is formed of a pair of similar flat skeleton plates arranged in planes which intersect at right angles to each other. Each plate is shaped to conform to the vertical 85 section of the receptacle and is but slightly smaller than the inner dimensions of the same.

Referring to Fig. 4 of the drawings 18 indicates one of the skeleton plates and 19 the other. These each comprise a rectangular upper portion conforming to the cylindrical portion of the receptacle and comprising the horizontal bars 20 and 21 and the vertical bars 22 and 23, and a semi-circular lower portion conforming to the curve or 90 hemispherical bottom 13 and comprising the semi-circular portions 24 and 25 which are extensions of the bars 22 and 23 respectively. Each frame is completed by a broad central bar 26 extending throughout the height of 100 the frame from the top bar 20 to the bottom curved portion 24. The bar 26 of the frame 18 is slotted as at 27 from the top downwardly and the bar 26 of the frame 19 is similarly slotted as at 28 from the bottom 105 upwardly. Each frame portion of the dasher is stamped out of a single piece of flat metal, and the device is assembled by sliding the frames longitudinally one upon the other, the slots 27 and 28 accommodating the corre- 110

sponding unslotted portions of the opposite frame.

29 indicates the dasher shaft. This is formed of a rod to the lower end of which 5 is secured a sleeve or tube 30. The tube 30 extends below the lower end of the rod 29 and is slotted as at 31 to receive the portions 20 of the dasher. After the parts are assembled they are secured together by soldering. 10 The shaft 29 extends above the arm 11 of the frame and the portion above said arm is slightly enlarged in diameter forming a head 32. The arms 9 and 11 are above and parallel with the axis of the trunnions 14 and 15 their front edges are notched as at 33 to receive the shaft. After the receptacle and the dasher are placed in the frame, in substantially the position shown in dotted lines in Fig. 3, they may be swung upon the trunnions until the shaft enters the notches 33.

Secured to the shaft 29 above the arm 9 is a gear 34 which meshes with a gear 35 mounted in the frame portion 4 upon a shaft 36 journaled in a sleeve 37 extending horizontally from the vertical portion 10 of the frame. Secured to the outer end of the shaft 36 is a crank 38 by means of which the dasher or agitator is operated. The gears 34 and 35 may be of any desired form but I prefer to 25 employ the spur gears shown in the drawings which are stamped out of heavy sheet metal. Pivoted to the frame 4 as at 39, is a latch 40 by means of which the shaft 29 is locked to the frame. The latch 40 turns down in front 30 of the upper notch 33 and is provided with an inwardly extending lip 41 which engages the head 32 of the shaft. When the shaft is locked the receptacle is also locked in the frame, but when the latch 40 is thrown back 35 as shown in dotted lines in Figs. 1 and 2, the receptacle and the dasher may be freely removed from the frame. To prevent the weight of the dasher shaft from tilting the receptacle sufficiently to spill its contents, 40 the portions 2 of the frame are arranged behind the receptacle, and the bottom 13 engages the same when tilted to the position shown in dotted lines in Fig. 3. Suitable means are provided to prevent turning the 45 drive mechanism except at such times as the shaft is locked in the frame. This comprises an ear or lug 42 on the latch 40, which, when the latch is thrown back enters between the teeth of the gear 35 preventing the gear from 50 rotating.

The shaft 29 passes through the closure 16 and the closure is provided with an upwardly extending sleeve 43 forming a bearing for the shaft to keep the dasher properly centered in 55 the receptacle. The closure is also provided with a depending annular flange 44 surrounding the shaft which prevents the agitated material within the receptacle from being ejected through the sleeve 43.

60 Having described my invention what I

claim as new and desire to secure by Letters Patent, is:

1. In a device of the class described, a frame comprising a pair of upright members connected substantially midway of their height by a yoke, and an upper frame portion, in combination with a receptacle trunnioned on said yoke, a dasher suspended within said receptacle and having a shaft detachably mounted in said upper frame portion, drive mechanism fixed in said frame and a gear fixed to said shaft and meshing therewith, substantially as described. 70

2. In a device of the class described, a frame in combination with a receptacle trunnioned therein, a pair of parallel horizontally disposed arms arranged one above the other and above said receptacle, a rotary dasher suspended within said receptacle and having a shaft detachably mounted in said arms and means on said frame for driving said shaft and dasher, substantially as described. 80

3. In a device of the class described, a frame in combination with a receptacle mounted therein, a dasher suspended within said receptacle and having a shaft detachably mounted in said frame, drive mechanism fixed in said frame, means for locking the receptacle and dasher in the frame, and means to prevent operation of the device except when in locked position, substantially as described. 90

4. In a device of the class described, a frame in combination with a receptacle trunnioned therein, a rotary dasher suspended within said receptacle and having a vertically disposed shaft detachably mounted in said frame, a pinion on said shaft, the crank shaft fixed in said frame and having a pinion for engaging with the pinion on the dasher shaft, a latch adapted to lock said dasher shaft in said frame when in one position, and in another position to lock the pinion on the crank shaft against rotation, substantially as described. 100

5. In a device of the class described, a frame comprising a pair of upright members, a yoke connecting the same and an upper frame portion in combination with a receptacle trunnioned upon said yoke, a rotary dasher suspended within said receptacle and having a shaft detachably mounted in said frame and suitable means for driving said shaft and dasher, said upright members of the frame constituting a stop to limit the swing of the receptacle on its trunnions, substantially as described. 115

In testimony whereof I have signed my name to this specification in the presence of 120 two subscribing witnesses.

ERNST SCHMITZ.
